UNITED STATES PATENT OFFICE.

JAMES WILLIAMSON, OF NEWPORT NEWS, VIRGINIA.

MACHINE FOR BLADING TURBINES.

1,172,334.

Specification of Letters Patent. Patented Feb. 22, 1916.

Application filed July 23, 1914. Serial No. 852,712.

To all whom it may concern:

Be it known that I, JAMES WILLIAMSON, a citizen of the United States, residing at Newport News, county of Warwick, State of Virginia, have invented a new and useful Machine for Blading Turbines, of which the following is a specification.

In a copending application filed July 23, 1914, Serial No. 852,713, I have described and broadly claimed a novel machine for securing blades and distance pieces in the blade carrying members of turbines and which is especially designed to be employed with blade carrying members which may be readily moved or handled. In my present invention, I have devised a novel machine for securing blades and distance pieces in turbine grooves, which is especially adapted to be employed for securing the blades in turbine casings, the weight of which, in some cases, is upward of seventy tons, thereby rendering them difficult of adjustment with respect to the blading machine.

With the above in view, my invention consists of a novel machine for securing blades and distance pieces in the groove carrying member of a turbine.

It further consists of a novel construction and arrangement of a tool and novel means for actuating the same.

It further consists of novel means for adjusting the stroke of the tool, whereby the necessity of moving the groove carrying member of the turbine is eliminated.

Other novel features of my invention will more clearly hereinafter appear in the detail description thereof.

For the purpose of illustrating my invention, I have shown in the accompanying drawing, one form thereof which is at present preferred by me, since the same will give in practice, satisfactory and reliable results, although it is to be understood that the various instrumentalities of which my invention consists can be variously arranged and organized, and that my invention is not limited except by the scope of the appended claims to the precise arrangement and organization of these instrumentalities, as herein shown and described.

Figure 1 represents a side elevation of a machine for securing blades in turbines, embodying my invention, in assembled position, with respect to a groove carrying member, the latter being shown in section. Fig. 2 represents an elevation of my device. Fig. 3

represents a section on line $x-x$ of Fig. 1. Fig. 4 represents a sectional elevation of the motor. Fig. 5 represents, in longitudinal section, a valve employed. Fig. 6 represents a cross sectional view of the valve.

Similar numerals of reference indicate corresponding parts in the figures.

Referring to the drawings:—1 designates a blade carrying member of a turbine, illustrated in the present instance as a casing member having a desired number of grooves 2 therein, with which the slots 3 communicate in order that the blades 4 and distance pieces 5 may be readily inserted therein.

6 designates beams or cross members supported on the member 1 and adapted to carry the angles or longitudinal members 7, which are connected by cross plates 8.

9 designates angles secured to the members 7 to form therewith, a support for the brackets 10, in which are journaled the trunnions 11 of the casing 12 of a motor whereby the latter is pivotally supported.

13 designates a bottom closure having a recess 14 therein, from which leads a groove 15, which communicates with a passage 16 in communication with a conduit 17 leading to the port 18 of a valve mechanism 19. The opposite end of the casing 12 is provided with a closure 20 having a groove 21 therein which leads to a passage 22 communicating by means of a conduit 23 with a port 24 of the valve mechanism 19. The valve mechanism may be located at any convenient place accessible to the operator, and for sake of illustration is shown as secured to the casing 12. The valve mechanism is provided with an inlet 25 adapted to be connected with the source of motive fluid supply, whereby the motive fluid is free at all times to enter the passage 26 of a valve plug 27, said passage 26 communicating with a transverse passage 28, adapted to be brought into and out of register with the ports 18 and 24. The valve plug 27 is retained against its seat by a flanged sleeve 29 and a nut 30. The valve plug is cut away on one side, as at 31, in order to form a chamber communicating with either the port 18 or the port 24 and with an exhaust port 32. The valve plug is recessed, as at 33, thereby forming shoulders 34 and 35, which serve as stops for the cap screw 36, which latter is fixed in position by means of a lock nut 37.

38 designates a handle secured to the valve plug 27 in any desired manner. The valve

mechanism may be located at any desired place, and in the present instance, I have shown the same as provided with apertured flanges 39 and 40, in order that the valve mechanism may be readily secured in position, and as illustrated, the same is shown as being carried by the casing 12.

The casing 12 of the motor is provided with a piston chamber 41, in which is adapted to reciprocate the piston 42 provided with a piston rod 43, which latter passes through the closure 20, said closure being provided with a stuffing box 44 of any desired type. The piston rod 43 also passes through a guide which consists of a yoke 45, in the present instance, which is secured to the flanged end of the casing 12 by means of fastening devices 46. The end of the piston 43 is provided with an eye or aperture 47, through which passes a bolt 48, provided with a nut 49. Said bolt also passes through one of the apertures 50 in the forked end of a lever 51, which is provided with a hub 52, through which passes a shaft 53, journaled in brackets 54, carried in any desired manner by the beams or members 7. The lever 51 has secured to its opposite end a pressing tool or blade 55 by means of fastening devices 56, said tool being adapted to travel in a turbine groove, as will now be set forth.

The operation of my novel machine for blading turbines will now be readily apparent to those skilled in this art, and is as follows: The blade carrying member, such as, for example, the turbine casing, has a wedge or stop inserted in the turbine groove 2, which is to be filled, said wedge or stop serving as an abutment for the blades and distance pieces. The blades and distance pieces are then inserted in the groove 2 through the slot 3 in front of the tool 55. The operator then actuates the handle 38 to bring the port 18 into register with the passage 28 in the valve plug, whereupon live motive fluid, entering through the inlet 25, passes through the passage 26 and passage 28 in the valve plug and through the conduit 17 into the piston chamber 41 in rear of the piston 42, thereby causing the latter to be advanced. This causes the piston rod 43 to rock the lever 51 on the shaft 53, and the tool 55 will be advanced in a curvilinear path and act as a pressing tool to fix the turbine blades and distance pieces in the turbine groove. The exhaust in front of the piston 42 takes place through the passage 22, conduit 23, port 24 of the valve mechanism, and exhaust port 32. The actuating handle 38 is then moved to bring the port 24 into register with the passage 28, whereupon live motive fluid will be admitted into the piston chamber 41 in front of the piston 42 and cause the latter to be moved rearwardly. The exhaust in the rear of the piston takes place through the pas-

sage 16, conduit 17, port 18, and port 32 of the valve mechanism. After a portion of the turbine groove has been filled with the turbine blades and distance pieces, the end of the piston rod 43 is connected with one of the other apertures 50 in the lever 51, thereby bringing the pressing tool 55, when in its initial position, in rear of the next succeeding slot 23, through which additional blades and distance pieces are inserted and fixed in position in the manner above described. The entire groove is filled in this manner with turbine blades and distance pieces, it being understood that the wedge or stop is removed and the place occupied thereby filled with turbine blades and distance pieces.

It will be seen that the piston rod travels in a rectilinear path, while the pressing tool travels in a curvilinear path or in the arc of a circle parallel to or concentric with a turbine groove. By the employment of my present invention, any desired number of turbine blades and distance pieces may be simultaneously fixed in position. Turbine blades and distance pieces are ordinarily secured in the turbine grooves by inserting the same separately into the groove and calking them in place by hand, the result of which is that it is necessary to rectify the blades and distance pieces. Such work not only consumes a large amount of time, but also requires skilled labor to properly do the work. Since the pressing tool travels in a curvilinear path, there is no chance for the turbine blades and distance pieces binding in the grooves.

It will be apparent that I provide means whereby the pressing tool may be made to travel over different portions of the work in a circular path having the lever axis for its center.

Owing to the manner in which the motor and its adjuncts are supported by the blade carrying member, and the manner in which the pressing tool is operated, the necessity of moving the turbine casing during the blading operation is entirely eliminated.

I am aware that it has heretofore been proposed to employ a pressing tool, which is reciprocated in a path substantially tangential to a turbine groove. My present invention is entirely differentiated from such construction, since I employ a novel construction and arrangement of motor and tool carrying member, and the pressing tool is reciprocated in a curvilinear path substantially parallel to the turbine groove, and to none of the constructions in the prior art do I herein make my claim.

It will now be apparent that I have devised a novel and useful machine for blading turbines, which embodies the features of advantage enumerated as desirable in the statement of the invention and the above

description, and while I have, in the present instance, shown and described a preferred embodiment thereof which will give in practice satisfactory and reliable results, it is 5 to be understood that the same is susceptible of modification in various particulars within the scope of the appended claims without departing from the spirit or scope of the invention or sacrificing any of its advantages.

Having thus described my invention, what I claim as new and desire to secure by Letters Patent, is:—

1. A machine for securing blades and distance pieces in turbine grooves, comprising a support, a motor movably carried thereby, a lever fulcrumed in said support and operatively connected with said motor, a tool rigidly carried by the end of said lever, 20 whereby said tool is made to travel in a circular path having the lever axis as its center.

2. A machine for securing blades and distance pieces in turbine grooves, comprising a support, a motor carried thereby, a lever fulcrumed in said support and operatively connected with said motor, a tool fixed to the end of said lever, whereby said tool is made to travel in a circular path having the lever 30 axis as its center, means whereby said tool may be made to travel over different portions of the work, and actuating means for said motor.

3. A machine for securing blades and distance pieces in turbine grooves, comprising a support, a motor carried thereby and provided with a reciprocating piston rod, a lever pivotally supported and having spaced apertures in one end thereof, a fastening 40 device passing through one of said apertures and connected with said piston rod and a tool rigidly fixed to the other end of said lever, whereby said tool is made to travel in a circular path having the lever axis as 45 its center.

4. A machine for securing blades and distance pieces in turbine grooves, comprising a support, a motor having trunnions journaled in said support and provided with a reciprocating piston and piston rod, a guide for said piston rod, means to control admission and exhaust of motive fluid to reciprocate said piston, a lever pivotally supported and having a forked end, into which 50 the end of said piston is adapted to extend, and means to secure the end of said piston rod at different points on said forked end.

5. In a machine for securing blades and distance pieces in turbine grooves, a support 60 consisting of longitudinal members, adapted to rest on the blade carrying member of the turbine, brackets carried by said members, a motor pivotally supported by said brackets and provided with a reciprocating piston and piston rod, means to control admission

of motive fluid to reciprocate said piston, a lever having a hub pivotally supported by said member, said lever having apertures at one end at different radial points thereon, means to connect said piston with a predetermined aperture, and a tool secured to the other end of said lever and adapted to travel in a curvilinear path. 70

6. A machine for securing blades and distance pieces in turbine grooves, comprising a support consisting of a plurality of longitudinal members and cross members connecting said longitudinal members, brackets carried by said members, a motor journaled in said brackets and provided with a reciprocating piston and piston rod, 75 actuating means for said motor to reciprocate said piston, a lever pivotally carried by said support, means to secure the end of said piston at different radial points on the end 80 of said lever, and a tool carried by said lever.

7. In a machine of the character stated a support adapted to be located above the turbine casing, a motor carried by said support and provided with a reciprocating piston and piston rod, a lever fulcrumed in said support and having its fulcrum on the horizontal axis of said casing, a tool fixed to the end of said lever, whereby said tool is made 95 to travel in a circular path having the lever axis as its center, and actuating means for said motor.

8. In a machine of the character stated a support adapted to be located above the turbine casing, a motor pivotally carried by said support, brackets carried by said support, a lever fulcrumed in said brackets, means to secure the piston of said motor to the end of said lever at different points, and 100 a pressing tool rigidly carried by said lever, 105 whereby the tool is made to travel in a circular path having the lever axis as its center.

9. A machine of the character stated, a lever pivotally supported, a radially directed 110 tool rigidly carried by said lever, whereby said tool is made to travel in a circular path having the lever axis as its center, means to oscillate said lever and means whereby said tool may be made to travel over different 115 portions of the work.

10. In a machine for securing blades and distance pieces in the groove of a turbine casing, a rotatable lever, a pressing tool rigidly carried by the end thereof, a support 120 for said lever, and means to actuate said lever, whereby said tool is made to travel in a circular path having the lever axis as its center.

11. In a machine for securing blades and distance pieces in the groove of a turbine casing, a motor pivotally supported, a piston rod therefor, a lever suitably fulcrumed, connections common to said piston rod and said lever, and a pressing tool rigidly car- 125 130

ried at the end of said lever, whereby said tool is made to travel in a circular path having the lever axis as its center.

12. In a machine for securing blades and distance pieces in the groove of a turbine casing, a motor pivotally supported, a piston actuated by said motor, a lever suitably fulcrumed and having upwardly and downwardly extending members, adjustable connections common to said rod and the upwardly extending member of said lever, and a pressing tool rigidly carried by said downwardly extending member, whereby said tool is made to travel in a circular path having the lever axis as its center, said pressing tool traveling in an arc concentric with the turbine groove.

13. A machine for securing blades and distance pieces in the groove of a turbine casing, comprising a support carried by the turbine casing, a motor casing fulcrumed on said support, a piston in the casing, a

piston rod, a lever pivotally mounted on said support, a pressing tool fixed to said lever, and means to control admission and exhaust of motive fluid to said casing to reciprocate said piston and thereby cause said tool to travel in a circular path having the lever axis as its center.

14. A machine for securing blades and distance pieces in the groove of a turbine casing, comprising a support, brackets carried thereby, a lever fulcrumed upon said brackets and having a bifurcated end, a motor, a piston therefor connected with said bifurcated end, a pressing tool rigidly secured to said lever, and means to actuate said motor, whereby said tool is made to travel in a circular path having the lever axis as its center.

JAMES WILLIAMSON.
